UNITED STATES PATENT OFFICE

THOMAS W. GREEN, OF PHILADELPHIA, PENNSYLVANIA.

COMPOUND TURBINE-ENGINE.

1,163,336.

Specification of Letters Patent.

Patented Dec. 7, 1915.

Application filed February 10, 1915. Serial No. 7,251.

To all whom it may concern:

Be it known that I, THOMAS W. GREEN, a citizen of the United States, residing at 3024 E street, Philadelphia, in the county of 5 Philadelphia and State of Pennsylvania, have invented a certain new and useful Compound Turbine-Engine, of which the following is a specification.

A purpose of my invention is to form 10 a fixed abutment upon the casing surrounding turbine blades so as to receive and reflect a steam jet which has impinged against a blade, diverting it from the front of the following blade and, preferably directing 15 it against the surface upon which it had just previously impinged.

A further purpose of my invention is to 20 vary the steam supply to a disk turbine by a rotatable cylindrical cut-off within the steam inlet space of the turbine.

A further purpose of my invention is to 25 provide rounded inlet approach surfaces for the steam passages of a disk turbine at the same time that the extent of opening of these rounded passages may be varied.

I prefer to illustrate my invention by but 30 two of the many forms thereof in which it may obviously be used, selecting two which are practical, efficient and relatively inexpensive and which at the same time well 35 illustrate the principles thereof.

Figure 1 is a vertical section of a turbine, transverse to the shaft, the view being broken away successively to show vertical 40 sections of one form of my invention. Fig. 2 is a section of the structure of Fig. 1 upon line 2—2 thereof, looking in the direction of the arrows. Figs. 3 and 4 are fragmentary enlarged vertical sections taken upon lines 45 3—3 and 4—4 respectively of Fig. 2, both looking in the same direction and corresponding in construction to two of the sections shown in Fig. 1. Fig. 5 is a fragmentary section corresponding to Fig. 4, showing a modification. Fig. 6 is a fragmentary section upon line 6—6 of Fig. 2.

Similar numerals of reference indicate like parts.

I will first describe the construction illustrated:—Upon the base 10 is mounted a semi-cylindrical lower casing 11, having bearing extensions 12 and supporting a co-operating semi-cylindrical upper casing comprising end plates 13, 13' and an intermediate half ring 14. They are held together by bolts 15. The lower casing re-

ceives anti-friction bearing metal at 16, which is held in place by caps 12'. The shaft 17 rests in this bearing metal and passes through stuffing boxes 18 of any convenient form. About the shaft 17 and within the semi-cylindrical casings, I place two facing partition supports 19, 19' which are preferably identical but placed right and left, facing each other. They do not rotate 65 but are secured to the casing as by bolts 20. Upon the shaft is keyed the hub 21 of disk 22.

For convenience I have arbitrarily considered one side as "forward" and the other as "reverse" and have used primed reference 70 characters to indicate those supports, partitions, blades, ports, etc., upon the "reverse" side of my construction.

The partition supports contain receiving 75 chambers 23, 23' for the inlet steam which enters through the upper casing parts at 24, 24'. The partition supports also carry the inner and outer partitions, as at 25, 26 and 25', 26' and receive intermediate annular partition rings shown as three in number, 80 27, 28, 29 and 27', 28', 29', upon which the annular partitions 30, 31, 32 and 30', 31', 32', are supported. The partitions at the same distance from the center on opposite sides, such as 31 and 31' are preferably 85 duplicates but face oppositely.

Within each of the receiving chambers for inlet steam, I place a ring cut-off 33 preferably connected with an annulus 34. Upon some form of extension of the ring, as upon 90 the annulus, I form an arc rack 35 engaged by spur 36, rotated by stub shaft 37, threaded at 38 and carrying a non-circular head 39 at one end of a non-circular neck 38' at the other end. The threading at 38 is 95 intended to be sufficiently tight within the opening to hold the spur in any position. Consequently, the shaft may be turned to turn the ring to any desired extent and will retain the ring cut-off in any position. 100 While the construction described could be made to perform this function, additional security is provided by jam nut 40. The thread at 38 makes the construction steam-tight at this point. The exhaust takes place 105 through pipe 41 from an annular exhaust chamber 42 within the ring.

The disk 22 carries two series of annular blade holders, one series upon each side, here shown as four in each series, 45, 46, 47, 48 110 and 45', 46', 47', 48'. The holders of the two sets at the same distance from the shaft,

such as 46 and 46', are preferably duplicates but face oppositely.

The inner partitions 25, 25', and the outer partitions 26, 26', as well as each of the intermediate partitions 30, 31, 32, and 30', 31', 32', are provided with ports numbered from the inner side outwardly as 49, 50, 51, 52, 53, and 49', 50', 51', 52', 53', of which all except 53 and 53' are given a slant (with respect to a radius at that point) one way or the other according to the direction of intended rotation of the adjoining blades.

It will be evident that all of the ports upon one side of the disk 21 will slope in a clockwise direction and all those upon the other side in a counter clockwise direction. In the form shown in Figs. 1 to 4, these successive sloping ports lie within nearly radial zones to coöperate with blades whose outer and inner limiting surfaces are substantially within radial lines. As distinguished from this, the ports shown in the form of Figs. 5 are staggered, those of one set having their discharge openings substantially within the same radial line as those of the second partition farther from the shaft and the discharge openings of intermediate partitions being in substantially another radial line staggered with respect to the radial line within which the discharge openings of the ports of the adjoining partitions lie. Thus in Fig. 5 the outlets from the ports in alternate partitions will be substantially in line radially, while the outlets from the ports of intermediate partitions will lie between the radial lines generally corresponding to the outlets from the ports of the adjoining partitions. Many other combinations can obviously be effected.

To coöperate with the two settings of ports shown in Fig. 4, for example, as contrasted with Fig. 5, two different types of blades are shown, the form in Fig. 4 comprising extended bases 54, 55, 56, 57 and 54', 55', 56', 57', spaced to allow inlets at 58 between the adjoining blades. The blades are concaved parallel with the shaft and provide active faces 59, 60, 61, 62, and 59', 60', 61', 62', nearly perpendicular to the direction of the adjacent inlet ports.

It will be noted that the spacings between the outer edges of adjoining blades in the same set are much greater than the spaces between the bases of the same, allowing longer register of these outer spaces with the receiving ends of the discharge ports into the outer partition and giving room between the blades for the steam which has acted upon the rear faces of one set of blades to impinge upon the reflecting surfaces 63 which I provide in cavities 64 upon the inner cylindrical faces of the several partitions.

In assemblage the disk hub is placed upon the shaft and the blade holders and blades are secured to the disk by any suitable means, as by screws 22', for example. The parti-

tions are fastened in the partition supports and the cut-off rings are put in place. The supports, partitions and rings are then placed upon the shaft on opposite sides of the disk and blades. The stuffing boxes and anti friction bearing rings are next put upon the shaft.

Within the half casing 11 the stub shafts 38 are screwed and the spur gears are put on them. The shaft is then lowered to place 75 and the bearing caps and upper casing parts are fitted about it.

In the passage of steam from the receiving chamber to its discharge, it enters the ports of the inner partition 25 through openings 80 65 in the ring 33, the edges of the opening 65 as well as of the adjoining ports being rounded in order that no abrupt edges may be presented whether the opening allowed by the position of the ring be full or partial. 35

The steam passes through the inlet ports 49 against the first set of blades when their openings 58 are opposite the outer ends of the inlet ports. The steam impinges against the faces 59 or 59' and as the blades turn it 90 is then deflected against the inner surface of the next outer partition. In order to prevent reflection of the steam from this partition against the forward face of the next succeeding blade, tending to stop the 95 rotation, I provide the cavities 64 of triangular or curved transverse section, the exact shape and size of which will depend upon various factors, including the exact contour and angular position of the surfaces 59 or 59', the distance from the shaft at which they are located and the distance between the adjoining blades. I design this cavity to present fixed surfaces which shall receive the rebound thrust of this steam and either return it to the space between the blades in such a direction that it shall not retard the next blades, or preferably return it upon the rear faces of the blades which it has just left, tending to further accelerate the movement of the blade. During this portion of the movement of the blade just discussed, connection with the next outer steam space is cut off, with the result that 100 the impetus of the steam between the two blades of this innermost set has been utilized and the steam has reached its normal expansion due to the size of this space between its blades before this space is connected with the port, 50 or 50' which is an exhaust to it but an inlet port for the next outer space. The steam between the first set of blades expands through these exhaust ports into the spaces between the next set of blades as 110 soon as the openings 58 therebetween register with the outlet ends of the ports 50, 50' when a corresponding action takes place against the surfaces 60, 60' of the next set of blades. There is corresponding temporary closure against exhaust from these 115

120

125

130

135

spaces also and corresponding reflection of the impact steam from the faces of the blades in the second series against the inner surfaces 63 of the next outer (third) partition which reflection is harmless, at least, and preferably is directed against the rear surfaces of the blades which it has just left, as in the preceding case, getting a further beneficial use from this steam.

10 The spaces between the blades of each series of blades are larger than the spaces between the blades of any series closer to the shaft, as a result of which the pressure between the blades in each succeeding series 15 will be less than that in the preceding series. As the spaces 58 between the third set of blades register with the ends of the ports 51, 51' which are their inlet ports (though discharge ports for the next preceding set of 20 blades) the steam between the second set of blades is exhausted and becomes dynamic for the next series of blades and this succession of operations is repeated throughout as many series of blades as there are stages to 25 my turbine.

The forms shown in Figs. 3 and 4, as well as upon opposite sides of Fig. 1 are direct reversals of each other and it is my intention to allow the one to coast when the other 30 is working. The description which I have given would be equally true of each but the direction of rotation caused would be opposite.

I recognize that it may not be necessary or 35 desirable to have more than one disk 22 upon the same shaft and so show but one such disk. I recognize also that even where a plurality of disks may be desired, it may not be best to place blades and partitions 40 upon both sides of each disk but show this form as that most economical of space and materials.

While I show equipment in size and power 45 for rotation in one direction equal to that for rotation in the other, I recognize that, particularly where a plurality of disks are used the blades mounted upon them and partitions, used in connection with these 50 blades may be greater in number or in size 55 for rotation in one direction than in the opposite.

In the form shown in Fig. 5, the same principle is involved as in that shown in Figs. 1 to 4, but the shape of blade is somewhat 55 different and the space between each pair of blades exhausts into a space between a pair of blades relatively staggered in position with respect to a radius at this point in the stage beyond, instead of into a space 60 between a pair of blades in substantially radial line from the space exhausting. The length of blade available to receive the impact of the steam is reduced in this form and for this reason the surface against which 65 the steam engages is formed more as a

70 pocket than as a plane surface, as will be evident from comparison of the surfaces 59², 60², 61² and 62², with the surfaces 59, 60, 61 and 62. There is also a corresponding slight difference in the rear of each of the blades where I prefer to project the base of cut-off 75 54², 55², 56² 57² somewhat so that the rest of the blade shall be offset from it, as at 66, 67, 68 and 69. This protects against any engagement of the steam with the rear surface 80 of the blade as it enters.

It will be evident that the concrete illustrations which I have shown in response to the requirement of the statute are illustrative merely and that in view of the description and discussion thereof herein contained, many other forms will suggest themselves to those skilled in the art, in which forms a part, at least, of the benefits of my invention may be secured.

85 It will be evident that the use of successive cut-offs to prevent escape of steam from one compartment of a radially staged series will be of advantage in holding the steam therein until the force of the impact has been utilized, and that this feature will prove desirable with widely variant forms of turbine blade.

90 It will be evident that recessing or caving, or otherwise altering the face of a partition adjoining the blade to render the steam reflected therefrom harmless at least and, preferably again useful, will be of advantage with widely variant arrangements of stages, with greatly different forms of 95 blades and even where the cut-off is not used.

It will be evident that the rounding of the inlet ring cut-off, as well as the adjoining port edges will be of advantage in all types of radial flow turbines, whether single or multi-stage.

100 It will be evident that the exact character of the chamfering of the interior edges of the innermost ports and cut-off can be of any desired character and have been shown as 110 rounded as representing the best form.

Having thus described my invention, what I claim as new and desire to secure by Letters Patent is:—

115 1. In a device of the character stated, a casing, a plurality of fixed partitions therein of successively increased diameter, forming annular channels between and having ports through the partitions terminating at their outer sides at an angle, a rotatable disk 120 and a plurality of sets of blades mounted upon the disk and revolving within the successive channels, the spaces between blades of adjoining sets, simultaneously registering in pairs with ports in the intervening partitions to provide flow of steam from the spaces between one set of blades to spaces between the next outer set of blades during the time of simultaneous registry, the blades of each set being provided with extended 125 130

bases adjoining the inner partitions to form cut-offs for the ports closing the outer ends of said ports in the partitions before the inner ends thereof are closed.

5. 2. In a device of the character stated, a casing, a plurality of cylindrical, concentric, stationary partitions therein having ports therethrough and forming channels between the partitions at varying distances from the axis of the partitions, a rotatable disk and a plurality of sets of blades upon the disk fitting within the channels between successive partitions having outlets from an inner set of blades and inlets to the next outer set of blades registering simultaneously in pairs with the respective adjoining ends of the partition ports and having the inlets to the inner set of blades and outlets from the outer set of blades closed during this time 20 of simultaneous registry.

3. In a device of the character stated, a casing, a pair of cylindrical partitions therein having ports for admission and discharge of fluid to the space between the partitions 25 and having at intervals about the inner surface of the outer partition faces at an angle to the cylindrical surface at this point, the surfaces at an angle being located between the ports through this outer partition, a rotatable disk and a plurality of blades mounted upon the disk and adapted to revolve between the two partitions, said blades being provided with surfaces transverse to the line of direction of fluid admitted through the 35 ports of the inner partition.

4. In a device of the character stated, a casing, a pair of spaced concentric cylindrical partitions provided with ports forming inlet and discharge passages to and from the 40 space between, the inlet ends of the ports having a direction at an angle to the radius, a rotatable support and a plurality of blades upon the support revoluble in the space between the partitions and provided with surfaces transverse to the direction of flow of inlet fluid, the outer of said partitions having surfaces upon its interior at an angle to its cylindrical surface for receiving and reflecting fluid after impingement of said fluid 50 upon the rear surfaces of the blades.

5. In a device of the character stated, a casing, a plurality of cylindrical, concentric, stationary partitions having ports therethrough and forming channels between the partitions at varying distances from the axis of the partitions, the ports in adjoining partitions being substantially in line radially, a rotatable disk and a plurality of sets of blades upon the disk exceeding in 55 number the number of ports and being a full multiple thereof, each space between blades of an inner set discharging into a space between blades of the next outer set out-of-line radially with the space discharging.

6. In a device of the character stated, a casing, a plurality of cylindrical, concentric, stationary partitions having ports therethrough and forming channels between the partitions at varying distances from the 70 axis of the partitions, the ports in successive partitions being substantially in line radially, a rotatable disk and a plurality of sets of blades upon the disk exceeding in number the number of ports and being a full multiple thereof, each space between blades of an inner set discharging into a space between blades of the next outer set out-of-line radially with the space discharging, and inner and outer spaces between 80 blades being connected in pairs, as described, simultaneously through each of the ports in the intervening partition in turn.

7. In a device of the character stated, a casing, a plurality of cylindrical, concentric, stationary partitions having ports therethrough and forming channels between the partitions at varying distances from the axis of the partitions, a rotatable disk and a plurality of sets of blades upon the disk 90 exceeding in number the number of ports and being a full multiple thereof, each space between blades of an inner set discharging into a space between blades of the next outer set out-of-line radially with the space 95 discharging, and inner and outer spaces between blades being connected in pairs, as described, simultaneously through each of the ports in the intervening partition in turn.

8. In a device of the character stated, a 100 casing, a series of concentric, cylindrical partitions therein having ports therethrough at an angle to the radius, the ends of the ports emerging at the outer surfaces of the partitions nearly midway between radii through the interior ends of said ports and the interior ends of the next adjoining ports on the sides toward which the ports slope, in combination with a rotatable disk and a plurality of sets of blades fitting between the partitions, the number of blades in each set being double the number of ports and each port discharging through the intervening partition from a space between blades of the inner set to a space between 110 blades in the outer set out-of-line radially with the space discharging.

9. In a device of the character stated, a 120 casing, a series of concentric, cylindrical partitions therein having ports therethrough at an angle to the radius, the ends of the ports emerging at the outer surfaces of the partitions nearly midway between radii through the interior ends of said ports and the interior ends of the next adjoining ports on the sides toward which the ports slope, in combination with a rotatable disk and a plurality of sets of blades fitting between the partitions, the number of blades in each set being double the number of ports 125 130.

and each port discharging through the intervening partition from a space between blades of the inner set to a space between blades in the outer set out-of-line radially 5 with the space discharging, both the inner and outer spaces being otherwise closed during the discharge.

10. In a device of the character stated, an outer casing and a pair of fixed, concentric, 10 cylindrical partitions of different diameter mounted thereon, providing a space between the partitions and having ports through the partitions at an angle to the radius, in combination with a rotatable support and a 15 plurality of impeller blades mounted upon the support having the number of blades at least twice the number of ports in each of the partitions, and an exact multiple thereof.
11. In a device of the character stated, an 20 outer casing and a pair of fixed, concentric, cylindrical partitions of different diameter mounted thereon, providing a space between

the partitions and having ports through the partitions at an angle to the radius, in combination with a rotatable support and a plurality of impeller blades mounted upon the support, having the outer and inner rear edges of each blade substantially in line radially, having the number of blades at least twice the number of ports in each of the 25 partitions and an exact multiple thereof.

12. In a device of the character stated, an outer casing, a turbine therein having generally radial flow and an interior steam chamber with ports along the outer boundary of the chamber in combination with a cylindrical cut-off apertured in general correspondence with said ports, a threaded pin passing through the casing and gearing between the pin and the cylinder. 30
